(57) **CLAIM**

The ornamental design for a lens with reticle, as shown and described.

DESCRIPTION

FIG. 1 is a front elevation view of a lens with reticle in accordance with my new design;

FIG. 2 is a reference view thereof showing the areas indicating from where enlarged details are taken;

FIG. 3 is an enlarged detail view of area 3 circumscribed within FIG. 2;

FIG. 4 is an enlarged detail view of area 4 circumscribed within FIG. 3;

FIG. 5 is an enlarged detail view of area 5 circumscribed within FIG. 3;

FIG. 6 is an enlarged detail view of area 6 circumscribed within FIG. 2 of a second embodiment of the lens with reticle;

FIG. 7 is an enlarged detail view of area 7 circumscribed within FIG. 6;

FIG. 8 is an enlarged detail view of area 8 circumscribed within FIG. 6;

FIG. 9 is an enlarged detail view of area 9 circumscribed within FIG. 2 of a third embodiment of the lens with reticle;

FIG. 10 is an enlarged detail view of area 10 circumscribed within FIG. 9; and,

FIG. 11 is an enlarged detail view of area 11 circumscribed within FIG. 9.

The dot-dash-dot broken lines are enlargement frames and lead lines that form no part of the claim. The broken line surrounding each of FIGS. 1 and 2 depicts the boundary of the claim and forms no part thereof. The evenly spaced broken lines in FIG. 1 and 2 depict text that forms no part of the claimed design. The evenly spaced broken lines in FIGS. 6–11 depict portions of the lens with reticle that form no part of the claimed design.
